(No Model.)

J. W. STOWELL.
EARTH CLOSET COMMODE.

No. 410,813.

Patented Sept. 10, 1889.

UNITED STATES PATENT OFFICE.

JOHN W. STOWELL, OF PUTNEY, VERMONT.

EARTH-CLOSET COMMODE.

SPECIFICATION forming part of Letters Patent No. 410,813, dated September 10, 1889.

Application filed June 30, 1888. Serial No. 278,665. (No model.)

To all whom it may concern:

Be it known that I, JOHN W. STOWELL, of Putney, in the county of Windham and State of Vermont, have invented a new and Improved Earth-Closet Commode, of which the following is a full, clear, and exact description.

My invention relates to an article of household furniture, combining a commode and an earth-closet in a manner not to indicate the presence of the closet when the structure is folded or closed, the whole making an inexpensive, ornate, and useful piece of furniture.

The invention will first be described, and then will be particularly pointed out in the claims.

Reference is to be had to the accompanying drawings, forming a part of this specification, in which similar letters of reference indicate corresponding parts in all the figures.

Figure 1 is a perspective view of my improved commode with the earth-closet in position for use, and with the excrement vessel, compartment, or box open. Fig. 2 is a vertical sectional view through the commode and open earth-closet. Fig. 3 is a vertical sectional view of the improvement, taken through the closed commode, the hinged front portion of the piece of furniture being in section on the line *xx* in Fig. 2; and Fig. 4 is an enlarged detail sectional view of the valved earth-box of the earth-closet, the valve being open.

The herein-described piece of furniture when it is closed has every appearance of a commode, and gives no clue from its design of its chief use, which is that of an earth-closet, as the following detailed description will disclose.

The commode is made in two main parts or sections, or a relatively stationary body or case A, and a hinged or swinging section B, in which latter the earth-closet and its appurtenances are arranged. The case A is provided with an upper drawer C, for holding towels and other toilet requisites, and at the top a few small shelves *aa* are preferably provided for holding toilet-bottles or other articles of use or ornament, as is common in articles of furniture of this general character.

The earth-closet section B is hung by hinges

b to one end of the case A, and at its other end the part B has a couple of headed pins *d* *d'*, which, when the commode is closed, are adapted for engagement by hooks *D D* on the case, for holding the whole compactly together. 55 The closet-section B is preferably provided with front casters E. At one end of it, preferably the right-hand end, the section B is provided with a box or compartment F, which has a front door *f*, which may be opened when 60 the section is closed within the case A, and is intended to hold an ordinary chamber-vessel, which thus will be readily accessible for use. At the side of this box F, and at the inside of the section B, are arranged the earth-closet 65 and its appurtenances, as next described.

The box or compartment G of the earth-closet is fixed to the front of the hinged commode-section B and does not open at the front of said section, which is preferably paneled 70 at its outside face to match the outside paneled door *f* of the compartment F; but this box G is provided at its rear side with a door H, which is provided all around its inner face, at or next the edges, with a rubber or other 75 suitable packing *h*, which makes an air and gas tight joint with the box to prevent escape therefrom into the commode or room of foul odors from the excreta-vessel I, which is placed in the box G, and directly under the seat-hole 80 *k* in the box-top K, which latter also preferably forms the top of the adjacent vessel-compartment F.

To a cleat *l*, fixed to the top board or plate K over the box F, is connected by hinges L 85 the bottom *m'* of the earth-box M, which, as shown most clearly in Figs. 2 and 4 of the drawings, is provided with a central opening *n*, communicating with a lower flange or collar N, which is fixed to the bottom of the box 90 and forms a case and seat for a conical valve O, which has a stem *o* extending up through the earth-storage space or chamber of the box and through the top of the box, and above it has a push knob or button P. A spring *o'*, 95 placed on the valve-stem between a collar *o'* on the stem and a skeleton guide *p* for the stem, which crosses the mouth of the earth-box, normally expands to close the valve O at the bottom of the flange N to cut off dis- 100

charge of earth from the box; but this discharge occurs whenever the button P is pressed to lower the valve.

The lower face of the box-top K is provided 5 with a packing m, like the one h, but arranged to close tightly to the top K around the seat-hole k to prevent exit of foul odors or gases therefrom.

Suitable catches R R are provided on the 10 box G to engage hooks or plates r r on the door H and hinged top K and draw their packings h m tightly to their seats to prevent escape of gases from the box G of the closet.

As this box and its appurtenances have 15 considerable weight, I provide the box with its own rear caster-wheel g, which, with the front casters E, gives substantial support to the entire hinged section B on the floor and allows it to be opened and closed easily.

20 To prepare the commode-closet for use, the box M will be filled with earth S, which may easily be done through the collar N when the valve O is held open while the box is swung over fully on its hinges L; or an opening in 25 the top of the box may be provided for filling it with earth. The filled box will then be lowered to the top or seat board K, and when the vessel I is placed in the box G and the door H is closed and latched the entire section B may be swung or rolled within the case 30 A, and fastened by the hooks D, or by a lock or other suitable device.

When the earth-closet is to be used, it is only necessary to unfasten the section B and roll 35 or swing it open from the case A, and then raise the earth-box M on its hinges, as shown in Fig. 1 of the drawings, and after the closet has been used the earth-box will be closed and locked to the seat-board K over the vessel I, and the valve head or button P will be touched or pressed down for an instant, which will open the valve O and let the earth, or some of it, fall into the vessel I to cover and deodorize the deposits therein, and the entire 40 hinged section may then be closed until it is convenient to remove the vessel I, which may quickly be done by opening the section B and the door H of the box G.

It is obvious that the arrangement within 45 the main case of a structure adapted for withdrawal therefrom and provided with two compartments—one for an earth-closet vessel and opening at the inside of the front of the structure, and the other for an ordinary chamber-vessel and opening at or through the outside of the structure—is a most convenient and useful construction because of the free access afforded to the ordinary vessel by simply opening a door and without withdrawing 50 the main earth-closet structure from the case. The novel hinging arrangement of the structure B and its earth-box M is also worthy of notice, because when the structure is opened said box, which is hinged to the inner 55 part of the seat-board K of the earth-closet,

may be quickly and easily swung back, so as to stop against the commode-case when the closet is in use. (See Fig. 1 of the drawings.)

It is obvious that I am not limited to the use of a structure hinged to the commode-case and provided with an earth-closet attachment at the inside and with an ordinary chamber-vessel receptacle which opens at or through the outside of the structure, as this principle of construction giving access to the chamber-vessel without exposing the earth-closet may be embodied in a structure fitted to slide into and out of the commode-case, and this I consider to be fairly within the scope of my invention, although the hinged structure is at present preferred.

Having thus described my invention, what I claim as new, and desire to secure by Letters Patent, is—

1. An earth-closet commode made with a 85 case, a structure fitted thereto and adapted for withdrawal therefrom, and provided with an earth-closet attachment opening at the inside of said structure and with an ordinary chamber-vessel receptacle, the latter having 90 an opening at or through the outside or front of the structure, substantially as herein set forth.

2. In an earth-closet commode, the combination of a case, a structure hinged thereto 95 and provided with two compartments F G, the one G forming an earth-closet-vessel receptacle and opening at the inside of the structure and the one F forming an ordinary chamber-vessel receptacle and opening at or 100 through the outside of the structure, and an earth-box or deodorizer-vessel hinged to the seat-board of the closet, so as to stop against the commode-case when the closet is adjusted for use, substantially as herein set 105 forth.

3. An earth-closet commode constructed with a case A and a structure B, hinged thereto and provided with a box F, opening 110 at the front or outside of the structure, an earth-closet box G, opening at the inside of the structure, and a valved earth-receptacle hinged to the top or seat board of the box G and adapted to discharge earth therein, substantially as herein shown and described.

4. An earth-closet commode constructed with a case A, having a drawer C, and a structure B, hinged to the case and provided with a box F, opening at the front or outside of the structure, an earth-closet box G, opening 120 at the inside of the structure, and a valved earth-receptacle hinged to the top or seat board of the box G and adapted to discharge earth therein, substantially as herein set forth.

JOHN W. STOWELL.
